FURNACE CONSTRUCTION

John W. Throckmorton, Wilton, Conn., assignor
to Petro-Chem Process Company Incorporated,
a corporation of Delaware

Application September 11, 1942, Serial No. 458,049

3 Claims. (Cl. 122—276)

My invention relates to new and useful improvements in tubular furnace construction.

The invention particularly contemplates vertical tubular furnaces of the type used in the heating of fluids both liquids and gases such as the distillation or cracking of hydrocarbons, chemicals, water and like products. Furnaces of this type have a combustion chamber which encloses a bank or banks of heat exchange tubes. These tubes provide a continuous passage through the combustion chamber for fluid to be heated. Heating gases are supplied to the combustion chamber by a burner or burners arranged to distribute the heat uniformly within the furnace. The gases rise vertically, circulating around the tubes and finally exiting via a flue passage opening through the top of the chamber. The fluid usually enters the furnace in a relatively cool condition. As the fluid passes through the heat exchange tubes it absorbs heat from the combustion gases and discharges from the furnace in a relatively heated condition.

I have now developed a construction for a furnace of the above character that is particularly applicable to small furnaces of from 1,000,000—5,000,000 B. t. u. capacity. In the combustion chamber I mount a bank of inverted U-shaped tubes which are interconnected to provide a continuous passage through the furnace for fluid to be heated. The tubes straddle the combustion chamber with their legs adjacent opposite walls thereof and with their transverse top portions bridging or spanning the upper end of the chamber.

The bank of heat exchange tubes may be easily fabricated in the shop and installed or removed as a unit. This construction facilitates cleaning, repairing or replacement of the tubes and permits ready access to be had to walls of the combustion chamber. Also making the tubes as a unit greatly reduces manufacturing and repair costs and effects a substantial saving in weight and in the quantity of material used in the fabrication.

I am aware of prior art constructions wherein heat exchange tubes have been arranged vertically in a combustion chamber with short radius return bend headers at their upper and lower ends. While the prior art construction is generally satisfactory, there is a much lower pressure drop in the fluid traversing the heat exchange unit embodying this invention, since the U-shape of the tubes provides long radius bends at the top of the unit. The pressure drop through the long radius bends is much less than

through the conventional short radius return bend headers.

An important object of my invention is to provide in an upright tubular furnace a bank of heat exchange tubes that are uniquely shaped and correlated to reduce the pressure drop in the fluids traversing the bank.

Another object of my invention is the provision of an upright tubular furnace that is susceptible of substantially complete shop fabrication and assembly, thus eliminating the erection costs and considerable weight, as well as substantially reducing the amount of material required in fabrication.

15 A further object of my invention is to provide a furnace in which all tubes may be cleaned from the ground without resorting to any ladders or elevated platforms.

Other objects and advantages of my invention 20 will be apparent during the course of the following description.

In the drawings forming a part of this specification and wherein like numerals are employed to designate like parts throughout the same,

25 Fig. 1 is a front view of a tubular furnace embodying my invention, parts being shown in elevation and parts in section for clearness of illustration,

Fig. 2 is a transverse sectional view, taken on the line 2—2 of Fig. 1,

Fig. 3 is a transverse sectional view, taken on the line 3—3 of Fig. 1,

Fig. 4 is a front view of a modified form of the furnace, parts being shown in section for clearness of illustration,

Fig. 5 is a vertical sectional view of the bank of heat exchange tubes shown in Fig. 4,

Fig. 6 is a transverse sectional view, taken on the line 6—6 of Fig. 5,

40 Fig. 7 is a fragmentary transverse sectional view taken on the line 7—7 of Fig. 5,

Fig. 8 is a fragmentary, vertical sectional view taken on the line 8—8 of Fig. 7,

Fig. 9 is a fragmentary vertical sectional view taken on the line 9—9 of Fig. 6, and

Fig. 10 is a fragmentary vertical sectional view of still another modification of the furnace.

In the accompanying drawings wherein for the purpose of illustration is shown a preferred embodiment of my invention, the numeral 15 designates a cylindrical metallic casing lined with a refractory material 16. The casing has a bottom 15a and the bottom is also lined with refractory material 16a. The top of the casing is closed by the flared lower end 17a of a stack

or flue passage 17. The space enclosed within the casing comprises a combustion chamber. Combustion gases are supplied to the chamber by a burner 18 extending through the bottom of the furnace. The entire structure rests upon a suitable supporting frame 19.

Within the combustion chamber is a bank of inverted U-shaped heat exchange tubes 20. As shown in Fig. 2, the widths of the U-bends 20 progressively decrease toward the ends of the bank so that the bank is essentially circular in transverse section. The lower ends of the tubes are arranged in a circle adjacent the wall of the combustion chamber and the tubes are interconnected by return bends 21 or any suitable design for continuous flow of fluid through the bank. I prefer that the lower ends of the tubes extend through the bottom of the furnace so that the headers 21 are readily accessible. Suitable covers 22 having hinged bottoms 22a enclose the headers. Each of the headers has a clean-out port normally closed by a removable plug. Solids in the fluid deposit on the walls of the tubes and these solids must be removed periodically. The construction here illustrated provides for easy cleaning of the tubes since it is necessary only to open the hinged bottoms 22a, remove the clean-out plugs and insert the cleaning element. The cleaner will pass through the upper bent tube section, since it has an essentially long radius.

Fluid to be heated enters the furnace through an inlet pipe 23 which connects with the bank of heat exchange tubes and discharges from the furnaces through a delivery pipe 24 connected at the opposite end of the bank of tubes. The fluid usually enters the furnace in a relatively cool condition and discharges therefrom in a relatively heated condition. As the fluid traverses the bank of heat exchange tubes it absorbs heat from the combustion gases. By placing the top bends of the tubes 20 transversely across the combustion chamber and directly in the path of the flue gas, the operation of the furnace to absorb heat from the combustion gases is particularly efficient. In addition, the provision of long radius bends at the top of the heat exchange bank greatly reduces the pressure drop in the fluid.

Fig. 4 shows a construction wherein the lower ends of the tubes 20 connect with an annular tubular manifold 25 supported by the bottom 15a of the furnace. Vertical partitions 26 at opposite sides of the manifold separate the same into chambers or compartments 25a and 25b. One leg of each heat exchange tube communicates with chamber 25a and the other leg thereof communicates with chamber 25b. Pipe 23 is connected to the header 27 which forms an outlet from chamber 25a and pipe 24 is connected to the header 28 forming an outlet from chamber 25b. As the fluid enters chamber 25a through pipe 23 it strikes a horizontal baffle plate 29 which spreads it evenly through the chamber and causes a substantially even distribution of the fluid in each of the heat exchange tubes. Manifestly all of the tubes will be in parallel and the fluid in chamber 25a will be transmitted to section 25b simultaneously through each of the tubes 20.

This unique arrangement provides a large number of tubes to be placed in parallel flow and provides excellent distribution of the fluid. Furthermore, there is a much lower pressure drop in the fluid traversing the heat exchange

tubes than in the construction shown in Fig. 1. The heat exchange unit can be assembled, tested and installed in the shop and it can be removed as a unit for cleaning or repair.

In Fig. 10 I show a construction wherein an economizer is provided in a stack 17 so that low flue gas temperature and high efficiency are obtained. The economizer, which may be associated with either the furnace shown in Fig. 1 or the furnace shown in Fig. 4, comprises inverted U-shaped tubular members 30 having outwardly bent end portions 30a and 30b which extend exteriorly of the stack. Inlet pipe 23 is connected to the end portion 30a and the end portion 30b is connected to an upward extension 20a of the heat exchange tubes by a connection 31. Economizer 30 and stack 17 are preferably made as a unit, and connection 31 and inlet pipe 23 are detachably connected to the end portions 30a and 30b so that the stack and economizer may be applied to or removed from the furnace as a unit. When the stack and economizer have been removed, easy access may be had to the bank of heat exchange tubes 20. The economizer may be an air heater for pre-heating the air to the burner instead of a pre-heater for the fluid charge to the furnace.

The bank of heat exchange tubes 20 and particularly the lower portions thereof will be subjected chiefly to radiant heat. Heat will be transferred from the gases to the fluid in the heat exchange tubes 20. Obviously then the gases will become cooler as they rise in the combustion chamber. However, considerable heat will be carried by the gases into the convection section or stack 17. By mounting the economizer 30 in the stack a substantial portion of this heat will be absorbed by the fluid traversing the economizer. At least a portion of the economizer tubes have radial fins 30c which provide extended surfaces for increasing heat absorption. Since the fluid flowing through the economizer will be relatively cool, it will be particularly efficient in absorbing heat from the exhaust combustion gases and will thereby enter the combustion chamber in a preheated condition, thus increasing the efficiency of the furnace.

It will thus be seen that I have achieved the objects of my invention. I have disclosed three modifications, each of which is susceptible of substantially complete shop fabrication and assembly, thus eliminating foundations and erection costs as well as effecting a considerable saving in weight and materials. Each of the furnaces may be easily disassembled when it is necessary to repair or replace parts. All of the heat exchange units are uniquely constructed so that there is very little pressure drop in the fluid as it flows through the furnace.

It will be understood that certain features and subcombinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, I claim:

1. A furnace construction comprising a cylindrical reinforced wall of refractory material providing a combustion chamber, a source of heat within the chamber, a bank of inverted U-shaped

heat exchange tubes of varying radii bridging the top of the combustion chamber and serially interconnected to provide a continuous fluid passage through the chamber, the straight portions of said U-shaped tubes arranged adjacent the wall of said chamber, and inlet and outlet pipes communicating with the U tubes having the smallest radii.

2. A furnace construction comprising a reinforced cylindrical wall of refractory material providing a combustion chamber, a source of heat within said chamber, a bank of inverted U-shaped tubes of varying radii, the straight portions of the tubes adjacent the wall of the chamber and the curved portion bridging the chamber, said U-shaped tubes serially connected to provide a continuous passage through the chamber, inlet and outlet pipes connected to the tube

bank, and spacing members bridging the tubes diametrically across the chamber to hold the tubes in fixed relationship with respect to each other.

5. 3. A furnace construction comprising a reinforced cylindrical wall of refractory material providing a combustion chamber, a source of heat within the chamber, a removable flue section enclosing the top of a combustion chamber, 10 a unitary prefabricated bank of inverted U-shaped heat exchange tubes including inlet and outlet connections said bank removably mounted into the combustion chamber from above, the straight portions of the U-shaped tubes adjacent the combustion chamber wall and the curved portions bridging the combustion chamber when installed.

JOHN W. THROCKMORTON.
